GAME APPARATUS

Joan E. Chamberlain, Livingston, Mont.

Application July 10, 1939, Serial No. 283,657

1 Claim. (Cl. 273—118)

The invention relates to game apparatus and more particularly to a game table or board.

The primary object of the invention is the provision of an apparatus of this character wherein through the use of a playing area or field and movable objects scoring may be had for the playing of a game and the winning of the same, the apparatus being effective for lending amusement and attractiveness to participants in the playing of the game.

Another object of the invention is the provision of an apparatus of this character wherein the playing field has certain identification or indicia and pockets distributed throughout the same so that in bringing an object in motion through rebound thereof it will roll or drop into a pocket and through indicia or identification effect a scoring for the player of a game and this maneuvering or activity of the object in motion requires of a player a certain amount of skill so as to master a high score for the winning of the game.

A further object of the invention is the provision of an apparatus of this character wherein the checks, tokens, or the like deposited by players for identifying selected plays can be collected and delivered into a depository, the delivery being had in a novel manner.

A further object of the invention is the provision of an apparatus of this character which is simple in its construction, thoroughly reliable and efficient in operation, being susceptible for use as a toy, lending attractiveness to participants or the players of a game thereby, being neat in appearance, possessed of artistic characteristics, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention and pointed out in the claims hereunto appended.

45 In the accompanying drawings:

Figure 1 is a plan view of the apparatus constructed in accordance with the invention.

Figure 2 is a side elevation partly in section.

50 Figure 3 is a vertical transverse sectional view thereof.

Figure 4 is a fragmentary sectional view taken on the line 4—4 of Figure 1 looking in the direction of the arrows.

55 Similar reference characters indicate corre-

sponding parts throughout the several views in the drawings.

Referring to the drawings in detail, A designates generally the apparatus in its entirety constructed in accordance with the invention and involves a table having corner legs 10, these being ornamented to give modernistic effect in the design thereof, and a table top or bed 11 which is formed with a flat upper surface carrying a playing field B which in its creation is made up 10 with longitudinal and transverse spaced parallel lines of demarcation, the top or bed being of elongated or substantially rectangular shape and these lines of demarcation present longitudinal and transverse rows of square spaces 12 having 15 centrally thereof arched spherical shaped pockets 13 for accommodating spherical shaped movable playing objects, one being identified at 14. The starting end of the playing field B is indicated by a blank space forming a starting station 15 20 and into this space or station is corralled the playing objects 14. One of the objects 14 is assigned to each player or participant in the use of the apparatus for the playing of a game as will be hereinafter described. 25

The field spaces 12 are colored of hues distinguishable from each other, that is to say, selected spaces 12 may carry a color yellow, others a color blue, and others a color red while combined with the color scheme of certain of the spaces are 30 symbols, for example, a five point star 16, a horse 17 or other symbols, not shown. While such spaces 12 are supplemented with respect to the color scheme and symbols by indicia as for example digits 18, these under the arrangement 35 thereof enable identification of such spaces by the participants or players of the game in the use of the apparatus.

For a major portion of one longer side, throughout one end thereof there is a minor 40 portion of the other longer side of the top or bed 11 for a marginal framing 19 equipped with a drop door arrangement at 20. That is to say, one door 20 is arranged at the major marginal framing area at one longer side of the said top 45 or bed 11, another at the end thereof and another at the minor marginal area at the other longer side of said top or bed. These doors 20 are actuated by control rods 21 and connections 22 therewith, the rods 21 being shifted by hand 50 levers 23 pivotally supported bracketed at 24 at one longer side of the top or bed 11. The upper face of each door 20 has created thereon spaces 25 corresponding to the spaces 12 in the playing field B carrying the symbols and color scheme 55

with the digits 18 omitted. These spaces 25 are for accommodating checks, tokens, or the like used by participants or players of a game by the apparatus and such checks, tokens, or the like 5 are selectively placed according to the election by the players of those spaces 12 in the playing field B to be played for scoring purposes in a game.

The doors 20 normally close communication to 10 a hopper 26 built beneath the top or bed 11 and housing a depository or collecting tray 27 so that the checks, tokens or the like can be recovered in the latter, they being dumped by the opening of the doors 20 which are manually controlled under manipulation of the levers 23. The doors 20 15 are normally in a closed position and lie flush relative to the upper surface of the bed or top 11.

The end of the top or bed 11 remote from the starting station 15 has fixed thereto a striking 20 canvas or sheeting 28 which rises above the playing field B and has roller shade-like connection with a rolling and unrolling shaft 29 journaled in brackets 30 mounted on side guard wings 31 attached to and rising from opposite sides of the 25 top or bed 11 next to the canvas or sheeting 28. The wings 31 are of a construction for the outward arching of the sheeting 28 to have the striking area of the latter curvilinear and thereby reversing the course of the ball on rebounding activity. This shaft 29 permits of the tightening or the holding taut of the canvas or sheeting 28 30 which is in the form of a striking curtain in that the spherical objects 14 when in play are projected or cast in a direction for the striking of the 35 said curtain and on rebound of these objects the same traverse the playing field B so that by chance they will drop and become seated in the pockets 13 present in the spaces 12. This action results in the scoring of points through determining valuations of scoring points in the playing of a game.

The top or bed 11 has associated therewith at one longer side of the same a scoring panel or board 32 bearing suitable indicia 33 indicative of

scoring valuations for the respective spaces 12 in the playing field B. For example, the spaces 12 carrying the symbol 17 have a scoring valuation of ten points, the symbol 16 a scoring valuation of five points, the spaces 12 being colored yellow 5 having a scoring valuation of three points, the red and blue colored spaces one scoring point valuation, and those spaces white a two point scoring valuation.

In the playing of the game it is necessary to 10 send an object 14 over the playing field B so that the striking of the curtain 28 may be accomplished by the object and through rebound of this object it will become deposited in a pocket 13 for 15 scoring purposes. The participant or player accumulating the highest scoring point is the winner of the game.

The top or bed 11 in the use of the apparatus must be sustained level so that the movable objects will not gravitate as would be the case when 20 traveling on an inclined plane of a playing surface.

It is to be understood of course that changes, variations and modifications may be made in the game apparatus and also that different games 25 may be played thereby as may come within the scope of the claim hereunto appended.

What is claimed is:

A backstop for a game apparatus having a horizontally disposed bed and thrown objects played 30 thereon, comprising side wings rising vertically from opposite side edges of said bed at one end thereof, a curtain roller disposed crosswise of the bed and journaled at the uppermost portions of said wings for the elevation thereof relative to said bed, and a flexible object rebounder curtain fixed to the bed and roller for disposition between the wings, the roller being adapted to render the curtain taut or slackened on the turning thereof, the said wings being constructed 40 for outwardly arching the curtain when rendered taut.

JOAN E. CHAMBERLAIN.
